[57] **CLAIM**

The ornamental design for a wheel spider, as shown and described.

DESCRIPTION

FIG. 1 is a front elevational view of a wheel spider showing my new design, it being understood that the broken lines are for illustrative purposes only;

FIG. 2 is a right side elevational view thereof;
FIG. 3 is a cross-sectional view thereof taken along the line 3—3 of FIG. 1;

FIG. 4 is a back elevational view thereof;

FIG. 5 is a front elevational view of a wheel spider showing a second embodiment of my new design, it being understood that the broken lines are for illustrative purposes only;

FIG. 6 is a right side elevational view of FIG. 5;
FIG. 7 is a cross-sectional view taken along the line 7—7 of FIG. 5; and

FIG. 8 is a back elevational view of FIG. 5.

FIG. 1

FIG. 2

FIG. 3

FIG. 4

FIG. 5

FIG. 6

FIG. 7

FIG. 8
